FOOD CUTTER

Samuel J. Popeil, Chicago, Ill.

Application November 12, 1958, Serial No. 53,341

Term of patent 14 years

(Cl. D55—1)

The dominant features of the design reside in the portions shown in full lines.

I claim:

The ornamental design for a food cutter, as shown and described.
